APPARATUS FOR ALIGNING PAPER AND CARBON SHEETS

William C. Pfeiffer, Dayton, Ohio, assignor to
The Egy Register Company, Dayton, Ohio, a
corporation of Ohio

Application September 27, 1933, Serial No. 691,181

5 Claims. (Cl. 197—128)

This invention relates to improvements in means for supporting and guiding a strip of fan-folded paper in which there is a plurality of superimposed strips that form the main strip.

5 It is particularly the object of this invention to provide, in connection with means for supporting and guiding a strip of fan-folded paper, means for supporting between the superimposed parts of the fan folded strip, sheets of carbon 10 together with means for varying the starting position of the carbon sheets with relation to the starting position of the fan-folded strip of paper.

It is an object to provide with continuous trans- 15 versely perforated fan-folded sheets a means of so supporting carbon sheets of lesser length than the sections of the paper sheets between perforations, that the carbon sheets can be moved successively from a position between the leaves of one 20 section of the paper sheets to another section of the paper sheets without interfering with the movement of the paper sheets and their folding.

It is a further object to provide such an arrangement whereby the paper sheets and carbon 25 sheets can move together as a unit, as well as independently of one another.

It is a further object to provide means of suspending the carbon sheets rigidly between the paper sheet folds from opposite sides of the paper 30 sheets so that a portion of the carbon sheets can be removed independently of the other sheets and reinserted independently of the other carbon sheets.

These and other objects will appear from the 35 following description taken in connection with the drawings.

Referring to the drawings:

Figure 1 is a front elevation of the apparatus with a part of the strip of paper broken away to 40 show the carbon sheet.

Figure 2 is a section on the line 2—2 of Figure 1.

Figure 3 is a section on the line 3—3 of Figure 2.

45 Figure 4 is a section on the line 4—4 of Figure 3.

The present apparatus is adapted to be used in connection with typewriters, but may be used with other instrumentalities to which a plurality of 50 superimposed strips of paper is to be fed.

The typewriter is indicated by the numeral 1 and has the usual platen 2 (Figure 2). On this typewriter is supported in any suitable manner a frame (Figure 1), which consists of side bars 3, 55 connected at their upper ends by means of a cross

bar 4, and at their lower ends by means of a cross bar 5. These two cross bars are braced by means of braces 6, which are riveted by means of rivets 7 to the cross bars and to each other by means of a rivet 8. The lower end of the frame is provided with brackets 9, by which the side bars are suitably attached to the frame of the typewriter.

On the lower ends of the side bars 3 and rotatably supported thereby is a shaft 10, which has thereon a pair of sprockets 11 (Figure 1). Around 10 these sprockets 11 run sprocket chains 12, which pass around another pair of sprockets 13 similarly located on the shaft 14, and rotatably mounted on the upper end of the frame between the two side bars 3. Each of the shafts 10 and 14 thus 15 has thereon a pair of sprockets connected by means of the sprocket chains 12. The upper shaft 14, instead of being supported directly by the side bars 3, is supported by means of two bars 15, each attached to one of the side bars by means 20 of screws, not shown. The upper ends of these bars 15 are connected by means of a rod 16.

On the upper end of the frame and attached to the side bars is a paper guide plate 17 (Figure 1). This plate is attached to the side bars by 25 means of rivets 18, and has adjacent each end thereof a slot 19 adapted to receive one end of a guide pin 20, adjustably supported in the slot by means of a screw 21. These pins may be adjusted to and from each other, and serve to 30 guide strips of paper 22 as they pass over a drum 23 mounted on the shaft 14 previously mentioned.

Slidably supported on the front of the frame and by the side bars 3 thereof, is a carbon supporting plate 24. This plate engages the side 35 bars at each end (Figure 3), and has struck up therefrom tongues 25, which fit behind part of the side bars 3 for guiding the plate 24 as it moves up and down on the side bars. The side bars 3 are U-shaped in cross section, with the 40 arms thereof projecting toward each other, and it is the front arms of these side bars that are engaged by the carbon supporting plate 24 and the tongues 25 struck up therefrom.

The carbon-supporting plate 24 is adjustably 45 attached to the chains 12 by means of pins 26, one mounted upon each end of a flat spring 27, which in turn is attached intermediate its ends to the carbon-supporting plate 24 by means of rivets 28. The plate 24 is provided with holes, 50 not shown, to receive the free ends of these pins 26. These pins 26 pass through links of the chains 12 for supporting the plate 24 on the chains. Each pin is supported at one end by the flat spring 27, while its other end is sup- 55

ported by the plate 24 when the plate is supported on the chains. The chains 12 are held in close engagement with the plate by means of loops 28. In the present instance there are two loops for each end of the flat spring 27. These loops prevent the chain from pulling the pins out of the holes so there is no danger of the carbon supporting plate being accidentally released from the chains during the operation of 10 the apparatus.

To the carbon supporting plate 24 is attached a carbon attaching plate 30, which extends laterally of the frame beyond each end of the carbon supporting plate. At one end of the carbon attaching plate is a pair of pins 31, while at the other end there is a similar located pair of pins 32. These pins are for the purpose of supporting carbon paper supporting strips. The pins 31 support one or more metal strips 33, to each 20 of which is attached one end of a carbon sheet (Figure 4). The pins 32 support one or more metal strips 34, each of which has therein holes to receive the pins. These pins are provided with notches 35 to receive the notched ends of a spring strip 36, adapted to fit over the outside face of the outer fold of the strip of paper.

By means of these metal strips 33, thus supported, sheets of carbon may be interposed between adjacent folds of the fan-folded strip of paper, the metal strips on one side of the frame projecting between certain folds of the strip of paper, while the metal strips on the other side of the frame will project between other folds of the fan folded strip of paper.

At the back side of the frame is a paper feed plate 37, connected at each end to each chain 12 by a rivet 38 passing therethrough. The feed plate 37 has at each end, on the upper edge thereof, a bracket 37a supporting a guide rod 38 therebetween by means of screw (not shown) extending through the brackets 37a into the ends of the rod. On each end of the guide rod 38, adjacent each bracket 37a, is a guiding disc 40 adjusted with relation to the rod 38 by means of a set screw 41. These discs 40 are spaced according to the width of the paper being used on the apparatus. The distance these discs are apart also corresponds to the distance the pins 20 are apart.

The feed plate 37 also has on its lower edge, at each end, a bracket 42 to which is pivotally attached one end of an arm 43 by means of bolts 44 (Figure 2). The upper end of each arm 43 has a stop 45 adapted to engage the upper edge of the feed plate. To the stop ends of the arms 43 is attached a finger bar 46 in the form of an angle iron, which has thereon aligning and feeding pins 47 adapted to pass through holes in the strips of paper and through holes provided therefor in the upper edge of the feed plate. The finger bar 46 is thus pivotally mounted on the bolts 44 with respect to the feed plate 37, and is urged toward the feed plate by means of a spring 48 connected at one end to the angle iron 43 and at its other end to the rod 38.

There is also provided on the feed plate intermediate its upper edges and between its ends, a second pair of brackets 49 which support a second guide rod 50. This guide rod serves to hold the strips of paper against the feed plate. This rod also cooperates with the rod 38 in holding the strips of paper in proper position when the aligning and feeding pins are withdrawn from the holes in the strips of paper.

In use, the strips of paper 22 extend over the

drum 23 at the top of the frame from a pile of paper located on some suitable support behind the typewriter. Each strip of paper 22 is divided by means of cross perforations 51 into sheets of sufficient size for the desired use. Adjacent the upper edge of each sheet of the paper strip are holes 52 for receiving the pins 47. The carbon sheets are indicated by the numeral 53, and are secured to their respective carbon-holding strips 34 in any suitable manner. The lower end of 10 each side bar is provided with a rubber stop disc 54 engaged by the paper feed plate when it is in its lowest position, and when the carbon supporting plate is in its uppermost position. On the upper one of the side bars 3 without the frame (Figure 1) is a spring housing 55, which incloses a coil spring 56. This coil spring has one end attached to the housing, while its other end is attached to the shaft 14.

In the operation of my invention, the paper strips 22 are passed through the paper feeding devices including the paper feeding plate 37, over the drum 23 and down the opposite side of the frame having the side bars 3. The carbon strips are then inserted between the paper strips 22 and mounted upon the carbon sheet carrier by slipping the metal strips 33 on to the pairs of pins 31 or 32. The strip 33 is then inserted with its end notches engaging the inner pins 31 and 32, holding the assembly in position. In this position the carbon sheets hang loosely down between the paper strips as shown in Figure 2.

Since the paper forms which compose the paper strips often bear printed matter upon which nothing is to be written or copied, it is unnecessary to employ carbon strips beneath these portions of the form. Accordingly, my invention provides means for adjusting the position of the carbon strips with respect to the paper forms by unlatching the latching pins 26 (Figure 40 3), which releasably lock the carbon carrier 24 to the chains 12. This is accomplished by pushing the free ends of the flat spring 27. The carbon-carrying plate 24 may be then slid up or down until the carbon sheets are adjusted bodily to the 45 locations where it is desired that copying shall begin. The ends of the spring 27 are then released, whereupon the pins 26 re-enter the links of the chains 12 and lock the carbon-carrying plate 24 in its new position. By this means, the 50 carbon plate 24 and its contents may be adjusted independently of the location of the paper-aligning and positioning devices, including the paper-feeding plate 37 and the positioning pins 47 (Figure 2).

With the carbon sheets thus inserted and adjusted, the operator releases the feeding rolls 1 of the typewriter, passes the ends of the paper strips 22 through the space beneath these rolls and the platen, re-engages the feeding rolls 1, 60 65 and advances the paper and the carbon strips into the typing position, turning the typewriter platen 2. As this is done, the paper strip moves the chains 12 by reason of its connection thereto through the paper-positioning pins 37 and the 65 rivets 38 attaching the paper feeding plate 37 to the chains 12. This motion of the chain moves the carbon-carrying plate 24 downward, as the paper-feeding plate 37 moves upward (Figure 2).

This action also winds up the coil spring 56, storing up energy which will tend to return the carbon-carrying plate 24 to its top position, as shown in Figure 2 when its sheets are released by the platen and the typewriter feeding rolls 1. The pins 47 may be engaged or released by push- 75

ing or releasing the finger bar 46, in an obvious manner, the paper having the usual apertures properly spaced to receive the pins 47 at the correct intervals between the successive paper forms.

After the operator types the required data, and the copies thereof are made by reason of the carbon sheets, he releases the paper-positioning pins 47 by pressing the finger bar 46, at the same time winding back the plate 2 by hand until the carbon sheets 53 are freed from engagement between the platen 2 and the said rollers 1. When thus freed, the carbon sheets 53 are drawn upwardly to their position of rest by the influence of the coil spring 54 acting through the shaft 14 upon the chains 12 and the carbon-carrying plate 24 located thereon. The operator then releases the typewriter feed rollers 1 and turns the platen forward, winding the typed paper forms 20 out to the end of the form and tears them off. He then returns the pressure rollers into their engaged position and repeats the foregoing operation upon the next set of forms.

While the carbon sheets are being fed into the space between the platen 2 and the feed rollers 1, the operator preferably places a finger lightly against the outermost paper form at a point between the carbon-carrying plate 24 and the platen 2, the friction between the carbon sheets 30 and the paper strips assisting in conveying both to the platen and feeding rolls without wrinkling.

It will be observed that the point at which copying will begin to take place may be instantly changed by changing the position of the carbon-carrying plate 24 on the chains 12, varying this, if desired, between successive forms. This is accomplished by unlatching the pins 26 (Figure 3), sliding the carbon-holding plate 24 up or down to the desired position and re-engaging the pins 26 in the desired position, as previously explained.

It will be understood that I desire to comprehend within my invention such modifications as come within the scope of my claims and my invention. It is understood that when I refer to transverse perforations that I refer to any form of transverse marking of the paper sheets, whether by printing, scoring, perforating or otherwise.

Having thus fully described my invention, what I claim as new and desire to secure by Letters Patent, is:

1. An article of manufacture for supporting, on a movable conveyor adapted to convey the article supplementary to any conveying action of the paper, a plurality of copy-producing sheets in-

terleaved between paper webs, said article consisting of a plate having on one side a guide portion for receiving and guiding said conveyor, a latching member cooperating therewith to releasably secure said plate to said conveyor, and 5 a holder on said plate for holding said copy-producing sheets whereby to adjust the position of the sheets with respect to the paper webs in order to vary the location at which copying commences on said paper, said holder comprising 10 spaced pairs of pins located near the opposite ends of said plate.

2. In combination with a frame to support and guide a strip of fan-folded paper, a shaft at each end of the frame, a drum on one of the shafts, a 15 pair of continuous chains on the shafts, each end of the drum having adjacent thereto a chain, means on the chains to engage said strip of paper, and means attached to the chains for supporting sheets of carbon between the folds of said strip, 20 said means comprising a plate having at each end a pair of pins and means on each pair of pins to hold a sheet of carbon.

3. An article of manufacture for supporting a plurality of sheets of paper on a pair of chains 25 consisting of a plate having on one side a pair of chain-receiving loops and a spring having thereon a pin for each loop adapted to extend through holes in the loop and the plate, and on the other side at each end a pair of pins. 30

4. An article of manufacture for supporting a plurality of sheets of paper on a pair of chains consisting of a plate having on one side a pair of chain-receiving loops and a flat spring attached intermediate its ends to the plate and 35 having on each end a pin extending through holes in the loop and the plate, and on the other side at each end a pair of pins.

5. In combination, a frame, a guide roller on one end of said frame, a platen at the other end 40 of said frame, a spaced chain carrier movably mounted on opposite ends of said frame adjacent the sides thereof, means on said carrier on one side of the chain for engaging a fan-folded strip of paper transversely perforated at intervals, means mounted on said carrier adapted to travel therewith and slidably engage the other and opposite side of said frame, means mounted on said last-mentioned means projecting inwardly between the folds of the paper strip to a point just within the opposite margins of the paper strip to support carbon sheets of lesser width than the paper strip and of lesser length than the distance between the transverse perforations 50 in the paper strip. 55

WILLIAM C. PFEIFFER.
